UNITED STATES PATENT OFFICE

DAVID H. EBINGER, OF COLUMBUS, OHIO, ASSIGNOR TO THE D. A. EBINGER SANITARY
MANUFACTURING COMPANY, OF COLUMBUS, OHIO, A CORPORATION OF OHIO

DESIGN FOR A WASH FOUNTAIN

Application filed July 27, 1931. Serial No. 40,695. Term of patent 14 years

To all whom it may concern:

Be it known that I, DAVID H. EBINGER, a citizen of the United States, residing at Columbus, in the county of Franklin and State of Ohio, have invented a new, original, and ornamental Design for a Wash Fountain, of which the following is a specification, reference being had to the accompanying drawings, forming a part thereof.

I claim:

The ornamental design for a wash fountain as shown.

DAVID H. EBINGER.
